GERSHOM MOTTO, OF BIG RUN, OHIO.

Letters Patent No. 65,763, dated June 11, 1867.

IMPROVEMENT IN WATER-ELEVATORS.

The Schedule referred to in these Letters Patent and making part of the same.

TO ALL WHOM IT MAY CONCERN:

Be it known that I, GERSHOM MOTTO, of Big Run, in the county of Athens, and in the State of Ohio, have invented certain new and useful improvements in "Water-Elevators;" and do hereby declare that the following is a full, clear, and exact description thereof, reference being had to the accompanying drawings, and to the letters of reference marked thereon.

In the annexed drawings, making part of this specification, A represents a box which is made of any suitable dimensions and placed over the top of the well. Lying across this box, and provided with proper bearings, is a shaft, H, said shaft having a crank-handle at one or both ends by means of which it is revolved. B represents a wheel, which is provided with four arms C C, which said arms are made forked at their ends, as seen. This wheel is secured upon the shaft H and revolves with it. D represents a chain with links long enough to reach from the fork of one arm to the fork of the next arm to it. This chain is made long enough to reach down into the water of the well, and is provided with two buckets, which are placed equidistant from each other. The wheel B is provided with a spout or trough, F, and the box A is also provided with a trough, G, as seen.

When the wheel B is revolved, the forks of the arms C carry the links around with them, and the links of course carry the buckets E E. When the buckets reach a position on the top of the wheel, the trough F is always immediately under them, and when the bucket is tipped over the trough receives it and pours it into the trough G; from which it runs out of box A into any receptacle placed to receive. More buckets may be used upon the chain, of course, and more troughs may also be used, but it is not desirable to increase the weight of water to be drawn up by using too many buckets.

Having thus fully described my invention, what I claim as new, and desire to secure by Letters Patent, is—
The arrangement of the chain D, provided on its inside with buckets E, with the wheel B having arms C C, and trough F, substantially as and for the purpose herein set forth.

In testimony that I claim the foregoing I have hereunto set my hand and seal this 19th day of February, 1867.

GERSHOM MOTTO.
